UNITED STATES PATENT OFFICE.

CHARLES EDWARD HAVILAND, OF LIMOGES, FRANCE.

DESIGN FOR A COVERED DISH, &c.

SPECIFICATION forming part of Design No. 23,964, dated January 29, 1895.

Application filed December 20, 1894. Serial No. 532,502. Term of patent 7 years.

To all whom it may concern:

Be it known that I, CHARLES EDWARD HAVILAND, a citizen of the United States, residing at the city of Limoges, in the Republic of France, have invented and produced a new and original Design for a Covered Dish and Similar Articles, of which the following is a specification, reference being had to the accompanying drawings, forming part thereof, 10 and in which—

The leading feature of my design consists in the new and original and ornamental form, shape and configuration of the covered dish, substantially as shown in the drawings forming a part of this application.

In the drawings A designates the body of the dish, and B the cover therefor.

The sides of the body A are composed of scalloped sections C and incline outward and downward, as shown, to a line adjacent to the horizontal plane of the bottom of the dish, at which line there is an ornamental edging D and from which said sides turn abruptly inward and downward to the base E. The opposite sides of the body A have suitable handles F, F.

The cover B has a raised center G bearing a handle H, and at its edges said cover has the scalloped sections I corresponding with the sections C of the body A and having the ornamental edging J corresponding with the edging D on said body.

The general form and shape of the body A and cover B constitute a harmonious and attractive outline.

What I claim is—

The design for a covered dish or similar article, substantially as shown and described.

Signed at the city of Limoges, in the Republic of France, this 6th day of December, 45 A. D. 1894.

CHARLES EDWARD HAVILAND.
